VEHICLE BODY

Filed July 2, 1928

UNITED STATES PATENT OFFICE

CHRIS E. SMITH, OF DETROIT, MICHIGAN, ASSIGNOR TO THE MURRAY CORPORATION OF AMERICA, OF DETROIT, MICHIGAN, A CORPORATION OF DELAWARE

VEHICLE BODY

Application filed July 2, 1928. Serial No. 289,641.

One of the objects of my invention is to provide an efficient and simple counterbalanced deck lid for vehicle bodies.

Another object of my invention is to provide in combination with such a counterbalanced deck lid, simple and convenient latching means therefor for securing the lid in its open and closed positions.

Another object of my invention is to provide in combination with the deck lid that will operate to restrain the lid in its approach to open and closed positions.

Another object of my invention is to provide in combination with a deck lid, spring means which will operate to pull against the restraint of the latches securing said lid to open and closed positions and thereby obviate rattling.

A further object of my invention is to provide in combination with such a lid and spring means for counterbalancing the same, anchors for the spring means to which said spring means may be adjustably connected for regulating their tension.

My invention consists in certain features of construction and combinations of parts to be hereinafter described with reference to the accompanying drawing, and then claimed, having the above and other objects in view.

Fig. 1 is a vertical longitudinal section taken through a vehicle body embodying my invention and showing the right-hand side of the body interior.

Fig. 2 is an elevation of the left side of the rear portion of the vehicle body embodying my invention having parts broken away to better illustrate the construction.

Fig. 3 is a vertical section taken longitudinally of a vehicle body embodying my invention and illustrating my deck lid latching means and one form of the remote control for said latching means.

Fig. 4 is a section taken on line 4-4 of Fig. 3.

Fig. 5 is a section taken on line 5-5 of Fig. 1.

Fig. 6 is a perspective of the anchor member to which the counterbalancing springs are attached.

Fig. 7 is a fragmentary sectional view

taken through the longitudinal center line of the deck lid and the transverse center line of the frame member against which it abuts when in open position, showing the means for latching the lid in open position.

55

Fig. 8 is a view taken on line 8-8 of Fig. 7.

Fig. 9 shows a modification in form of the spring anchor members which may be embodied in my construction.

I have shown a passenger vehicle body 60 designated generally by the numeral 10 having a passenger compartment 11, and to the rear thereof, an enclosed deck section designated generally by the numeral 12. In the top of the section is provided a movable lid 65 15 which conforms to the upper surface line of the section, and to which is secured at its under sides and intermediate its ends supporting brackets, 16 on the right side, and 17 on the left side. These brackets are in 70 the general form of a Y with the ends of the two adjacent legs of the Y suitably secured to the lid 15. The brackets 16 and 17 are secured at the converging point of their legs to pivots 18 and 19 which in turn are secured to the intermediate portion of the frame members 20 and 21. To the ends of the unattached arms 22 and 23 of the Y members 16 and 17 are attached the ends of coil springs 24 and 25. Secured to the horizontal sill members 27 and 28 of the body, 75 forwardly of the frame members 20 and 21 are anchor plates 29 and 30 having upper edges provided with a plurality of apertures as shown. The unattached ends of the 80 springs 24 and 25 are hooked into the apertures of the plates 29 and 30. These apertures in the upper edge of the plates 29 and 30 are utilized to adjust the tension of the springs 24 and 25, which may be done by 85 hooking the ends of the springs in the apertures which are the proper distance from the ends of the Y legs 22 and 23 to give the springs the desired tension.

The modification shown in Fig. 9 consists 95 in forming the anchor plates 29 and 30 with apertured inclined edges shown positioned to face the arcs described by the legs 22 and 23 in their movement. The springs 24 and 25 may then be attached so that their ten- 100

sion is unequal at the different points in the arc travelled by the ends of the Y legs 22 and 23, thus causing the spring on one side to exert a greater pull on its Y leg when the lid 15 is in closed position than it will when the lid is in open position, and causing the opposite spring to exert its greatest pull when the lid is in open position. The springs therefore are not in full tension at the same time thereby diminishing the effort necessary to force the lid into open or closed positions, while providing sufficient pull on both sides of the lid to prevent racking or such unequal wearing at the pivot points 18 and 19 as would throw the lid 15 out of alignment with the edges of its opening in the deck. This result can also be attained with the anchor means shown in Figs. 1, 2 and 6 by positioning the Y legs 22 and 23 at an angle to one another,—for instance, so that the leg 22 and spring 24 are in the same plane just prior to the point where the lid reaches closed position, and the leg 23 and spring 25 are in the same plane just prior to the point where the lid reaches open position.

Attached to the forward edge of the lid is a latch plate 31 which has a suitable aperture therein adapted to receive the latch bolt 32 which is secured by a case plate 33 to the under side of the transverse frame member 34. This latch bolt and case plate may be of conventional construction having the usual spring means incorporated therein and tensioned to force the latch bolt in the direction of the latch plate 31. One end of the latch bolt 32 is provided with an eye 35 in which is hooked a pull rod 36 which extends beneath the panel 37 into the passenger compartment 11, and is there attached to a lever 38 which is suitably pivoted as at 39, Fig. 5, to the frame member 40 and provides means for operating the latch bolt 32 from the passenger compartment 11. The rear edge of the lid 15 is provided with a U-shaped socket 42, Fig. 8, in which is secured a spring member 43 which is adapted to expand and grip the knob 44 secured to the rear side of the frame member 45. This latch serves to retain the lid in open position. When the lid is applied to those vehicle bodies which have enclosed passenger compartments and have a vertically slideable rear window 50, Fig. 3, in such compartment, it is necessary that the remote control means for the latch bolt 32 pass around the path of the slide window 50 and this is accomplished by forming a crank 51 on the end of a rod 52, Fig. 4, and attaching such crank to the eye 35 of the latch bolt and forming another crank 53 on the opposite end of the rod 52 and securing the end of the pull rod 36 to the end of this crank 53. The rod 52 is pivotally secured by brackets 55 and 56 to the forward side of the frame member 34 and extends laterally from the latch

bolt 32 a sufficient distance so that the end upon which the crank 53 is formed will permit the pull rod 36 to pass into the passenger compartment 11 at one side of the path of the sliding window 50. Within the passenger compartment and conveniently positioned for manual operation is a pivoted lever or handle 57 which is pivoted to the side of the compartment as at 58 and to which the end of the pull rod 36 is attached as at 59.

If desired, a suitable back cushion 60 may be secured to the under side of the lid 15 and a suitable seat cushion 61 may be positioned in the lower adjacent portion of the section so that when the lid is opened, the lower edge of the seat cushion 60 comes to a rest at a point adjacent the rear edge of the seat cushion 61.

Formal changes may be made in the specific embodiment of the invention described without departing from the spirit or substance of the broad invention, the scope of which is commensurate with the appended claims.

What I claim is:

1. In a vehicle body having an enclosed deck portion, a movable lid for said deck, supporting means for said lid pivotally secured to the side frame members of said body and adapted to carry said lid to a substantially vertical position when open and to a position conforming to the line of the deck when closed, a pair of coil springs each attached to said lid supporting means, anchor means for each of said springs secured to the frame members of said body, each of said anchor means having a plurality of points to which the ends of said springs may be secured whereby the tension of each of said springs may be individually adjusted for counter-balancing said lid in its movement with said supporting means.

2. In a vehicle body having an enclosed rear deck section, a movable lid for said section, pivoted supporting means for said lid whereby it is rotated about an axis to open and close, a pair of tensioned springs each anchored to said body and each attached to said pivoted supporting means, one of said springs being adjusted to exert its greatest pull toward open position when said lid approaches and is in its closed position, and the other of said springs being adjusted to exert its greatest pull toward closed position when said lid approaches and is in its open position.

3. In a vehicle body having an enclosed rear deck section, a movable deck lid conforming to the lines of said body and giving access to said section, a bracket secured to each side of said lid intermediate the ends thereof and each pivotally secured to the upright frame members of said body and having depending arms thereon, spring members attached to the depending ends of each of said

arms and to the horizontal frame members of said body, one of said arms and spring members cooperating to exert a constant opening effort on said lid when approaching and in closed position, and the other of said spring members and arms cooperating to exert a contrary effort on said lid when approaching and in open position, and latch means for retaining said lid in either open or closed position.

CHRIS E. SMITH.
